GEAR SHIFT HOUSING FOR A BICYCLE

Hans-Jurgen Lannoch, Hochstetten, Germany, assignor to
Fichtel & Sachs AG, Schweinfurt, Germany

Filed Feb. 19, 1971, Ser. No. 117,221

Claims priority, application Germany Nov. 27, 1970

Term of patent 14 years

Int. Cl. D12—16

U.S. Cl. D90—1

FIG.1

FIG.2

FIG.3

FIG.4

FIG.5

FIG. 1 is a side elevational view of a gear shift housing for a bicycle embodying my new design;

FIG. 2 is a top plan view thereof;

FIG. 3 is a rear elevational view thereof;

FIG. 4 is an elevational view taken from the side opposite to that of FIG. 1; and

FIG. 5 is a front elevational view thereof.

The cross bar of the bicycle and the gear shifting lever are fragmentarily shown in chain-dotted lines for illustrative purposes only.

I claim:

The ornamental design for a gear shift housing for a bicycle, as shown and described.
